(57) **CLAIM**

The ornamental design for a vehicle light, as shown and described.

DESCRIPTION

FIG. 1 is a perspective view of a vehicle light showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof with a cable coupled to the vehicle light.

The broken lines in FIGS. 1-8 illustrate portions of the vehicle light in which the design is embodied that form no part of the claimed design. The broken lines of the cable in FIG. 8 illustrate the environment of the claimed design, the dash-dot-dot-dash broken lines FIG. 8 illustrate the omission of the cable. None of the broken lines form part of the claimed design.
